DOUBLE-SEAMING MACHINE.

1,424,499.

Specification of Letters Patent. Patented Aug. 1, 1922.

Application filed January 10, 1918. Serial No. 211,118.

To all whom it may concern:

Be it known that I, SAMUEL McCULLOCH, a subject of the King of Great Britain, residing at the city and county of San Francisco and State of California, have invented 5 new and useful Improvements in Double-Seaming Machines, of which the following is a specification.

This invention relates to a double seaming 10 machine.

One of the objects of the present invention is to provide a double seamer which is particularly adapted for seaming differently shaped bodies, such as square, rectangular 15 and oval shaped cans, and which is also adapted to handle round cans of various sizes. Another object of the invention is to provide a seaming machine in which cams, positive movements and fine adjustments are 20 practically eliminated, and in which the seaming members are movably actuated by the periphery of the can end to be seamed. Another object of the invention is to provide 25 a floating support for the seaming member and in conjunction therewith to provide means for exerting a constant pressure on the seaming member particularly when seaming cans of different shapes. Another object of the invention is to provide 30 a novel spindle structure and means for intermittently rotating the same in conjunction with the spindle cage and the can table. Further objects will hereinafter appear.

The invention consists of the parts and 35 the construction and combination of parts as hereinafter more fully described and claimed, having reference to the accompanying drawings, in which—

Fig. 1 is a central, vertical section 40 through the machine.

Fig. 2 is a cross section, taken on line 2—2 of Fig. 1.

Fig. 3 is a plan view in cross section, 45 taken on the line 3—3 of Fig. 1.

Referring to the drawings in detail, A indicates the main base plate of the machine which, in the present instance, is supported 50 upon a pedestal or foot frame generally indicated at 2. The base member A is hollow, as shown, to form a chamber for the reception of the driving gears, generally indicated at 3 and 4, and also serves as the support for the main driving shaft 5 from 55 which power is transmitted through a pair of worm gears 6 and 7 to drive the gears 3

and 4. The gear 3 is secured on a vertically positioned shaft 8, on the upper end of which is secured a driver 9 which actuates a "Geneva" disk 10. This disk is secured on the lower end of a sleeve 11 forming a part 60 of the can-receiving table, generally indicated at 12. The "Geneva" drive shown serves the function of intermittently rotating the can-receiving table and it also serves the function of intermittently rotating the 65 spindle cage, generally indicated at 13.

The can-receiving table and the spindle cage will, of course, move in unison and it is, therefore, necessary to provide an independent driving shaft from which power may 70 be transmitted to intermittently drive the spindles indicated at 14. This is accomplished in the following manner: Secured on a center plate 15, forming a part of the table or base plate A, is a standard or column 16. Journaled in said standard is a shaft 17 which is driven through the worm drive comprising the gears 4 and 7, and secured by means of a feather on the shaft, near the upper end, is a driving gear 18 80 which remains in constant mesh with driving pinions 19 turnably mounted, one on each spindle.

Formed on the lower face of each driving pinion is a jaw clutch member 20 and slidably mounted on a feather on each spindle is a cooperating jaw clutch member 21. These clutches are automatically thrown into engagement during the intermittent rotation of the spindle cage by means of a stationary cam 22 secured on the upper end of the column 16; movement being transmitted from the cam to the lower clutch members 21 by levers 23, each of which is pivoted, as at 24, in an arm forming part of a collar 95 25 secured in the lower part of the spindle cage.

One end of each lever 23 is provided with a roller 26 which travels in constant engagement with the cam 22, while the opposite 100 end of each arm 23 is fork-shaped, as shown at 27, to straddle the clutch members 21 and to engage pins 28 formed thereon. The stationary cam 22 is of the hill and dale type, there being two rises and two depressions in the cam, as will hereinafter be described. It can therefore be seen that during the rotation of the spindle cage when a roller strikes a depression in the cam it will 105 rock the cooperating lever 23 about its pivot 110

24, thereby raising the clutch member 21 into engagement with its cooperating member 20. A driving connection is thus formed which permits a rotary movement to be transmitted to the spindle when a seaming operation takes place. The cam maintains each clutch in engagement while the spindle is in alignment with the first operation seamer and while it is in alignment with the second operation seamer. It then automatically disengages, due to the rises formed in the cam, to permit the can that has passed through the seaming rollers to discharge and simultaneously to permit a new can to be admitted.

The machine here shown is double in operation; that is, it is provided with two can feeding mechanisms generally indicated at 30 and two can removing arms 31. Each spindle, therefore, handles two cans during each complete revolution of the can table and spindle cage, thereby doubling the capacity of the machine and also permitting a more perfect seaming operation than is usually obtained, this being due to features which will hereinafter be described.

The seamer is provided with two first operation seaming rollers, generally indicated at 32, and two second operation seaming rollers, generally indicated at 33. These rollers are identical in construction and mounting and form one of the important features of the present invention. Each seaming roller may be termed a "floating roller" and it should be observed that no cams are required for their operation as each seaming roller is movably actuated by the periphery of the can end to be seamed, this being particularly true when different shaped cans, such as square, rectangular or oval, are being handled.

The mounting of the seaming rollers is more particularly shown in Fig. 1. It consists of a cylinder 34, in which is slidably mounted a piston 35. Pivotaly mounted on a wrist pin 36 carried by the piston is an arm 37, and journaled in the outer end of said arm is a seaming roller 32. Secured to the inner end of the piston is a corrugated flexible tube 38, the outer end of which is secured between an inner shoulder 39, formed on the cylinder, and a cylinder head 40. This method of securing the flexible tube permits air pressure to be exerted with in the tube without any danger of leakage, air being supplied from any suitable source, as a tank or the like, through means of a pipe 41 which may be located in any suitable position. However, I prefer to divide the pedestal or base 2 into two separate air chambers as diagrammatically indicated at 96 and 97 which may be charged from any suitable source and to connect the first operation cylinders with one tank and the second operation cylinders with the opposite

tank. This is of considerable importance as the last seaming operation generally requires more pressure than the first seaming operation. By dividing the tanks and supplying the first operation cylinders with air from one tank and the second operation cylinders with air from the opposite tank it becomes possible, for instance, to maintain thirty pounds pressure in the first tank and thirty-five pounds pressure in the second tank, this pressure being regulated by any suitable means and dependent upon the piston area exposed.

Each cylinder 34 is supported in a bracket 42 which is vertically adjustable with relation to the table A by an adjusting screw 43, and each cylinder is also longitudinally adjustable in a bracket proper by an adjusting screw 44. This is of importance as it permits the seaming rollers to be adjusted for cans of various diameters and heights. The outward movement of each piston 35 is controlled by a bell-crank 45. Each bell-crank is pivotally mounted, as at 46, in an extending arm formed on each cylinder, one end of said bell crank being pivotally connected to the shaft about which the seaming roller revolves while the opposite end is provided with an adjusting screw 47 which engages a pad formed on the cylinder.

Practically all adjustment, as far as the seaming rollers are concerned, after the machine has been set for a certain sized can, is taken care of by the adjusting screws 47; that is, if, when the machine is first started, it is found that the seam is not sufficiently tight, it is only necessary to slightly release the screws 47 which permits the seaming roller to advance slightly with relation to the can or to exert more pressure thereon. Also if the seam is found too tight it is only necessary to tighten the screw and partly withdraw the roller. In this way it is possible to quickly adjust any seaming roller employed and as the rollers are in a sense stationary particularly when operating on round cans and in a position where they may be conveniently reached the operation of adjusting same is simple when compared with most machines now employed.

The pins 28, by which the lower spindle clutch members 21 are raised and lowered, are not formed on the clutch members 21 direct but they are carried by a collar 21^a mounted below the clutch members 21; a ballrace 21^b being interposed between the collars 21^a and the clutch members 21. The collars 21^a and 25 are therefore locked against revolution about or with the spindle because the collars 25 are rigidly secured in the spindle cage. The clutch members 21 will, however, revolve, when raised into engagement with the clutch sections 20, as these are continuously driven from the gear 18 through the gears 19. It is therefore

- necessary not only to throw the clutches 21 into and out of engagement at predetermined intervals during the revolution of the spindle cage but it is also necessary to stop 5 the spindles 14 against revolution when predetermined positions are reached, this being particularly true at the point where the can bodies are fed to the can table and when square or oval cans are being handled.
- 10 The necessity for stopping the spindles in a predetermined position when a can is received can readily be appreciated when it is taken into consideration that a chuck 14^a is secured on the lower end of each spindle 15 and that this chuck must positively register with a can when it is delivered to the table.
- This positive and perfect register is obtained by forming an arm 50 on each clutch member 21. The outer end of each arm 50 20 is provided with a roller 51 and this roller is adapted to engage a stationary cam member consisting of two sections 52 and 53 formed above the cam 22. The clutches are thrown into engagement a moment previous 25 to moving into alignment with the first operation rollers 32 and they are continuously revolved until they leave the second operation rollers 33. The clutches are immediately thrown out of engagement when 30 leaving the second operation rollers and they are also positively stopped at this time by the cams 52 and 53 as the rollers 51, during the revolution of the clutch 21 and the movement of the cage, will strike the cams 52 and 35 53, thereby stopping the revolving movement of the spindles and also securing same in predetermined positions. This permits a can already seamed to discharge and permits a can to be seamed to be delivered directly 40 under a spindle chuck 14^a at the opposite points by the separate feeding mechanisms indicated at 30.

The operation will be as follows: With power applied to the driving shaft 5, it can readily be seen that shaft 17 and the gears 45 18 and 19 revolved thereby will be continuously operated as movement is constantly being transmitted through the worm drive, comprising the gears 4 and 7. 50 It can also be seen that the can table 12 and the spindle cage will be intermittently revolved through the "Geneva" movement which is driven by the gears 3 and 6.

A can with a top already placed thereon 55 may, therefore, be delivered to the can table by the feeding mechanism indicated at 30 when the table and the spindle cage come to a stop and as the spindle chucks are standing at rest at this position and in absolute alignment 60 with the cans it is possible to obtain perfect register. The operation of the "Geneva" movement will then move the can table and the spindle cage to a position in alignment with the first operation rollers 32, 65 the cans being raised into engagement with

the spindle chucks 14^a during this movement by cam members 60 formed on top of the table A which engage rollers formed on the lower end of plungers 61. These plungers serve the function of raising the cans 70 into engagement with the spindle chucks and the cans are, therefore, rigidly clamped between the plungers 61 and the chucks 14^a when the first operation rollers are reached. The cam 22 has simultaneously thrown the 75 clutch members 20 and 21 into engagement, thereby bringing the spindles up to the desired speed when the rollers 32 are reached.

The table and spindle cage remain stationary at this point until the first seaming 80 operation has been performed. The "Geneva" movement will again partly rotate the can table and the spindle cage and bring the cans into register with the second operation rollers 33 where the final seaming 85 operation is performed. Both the cage and the can table remain stationary at this point due to the intermittent action of the "Geneva" movement and it should also be understood that a second set of cans is being operated upon by the first operation rollers and that new cans to be seamed are simultaneously being delivered by the feed mechanism 90 30. The next operation of the "Geneva" movement turns the can table and the spindle 95 cage to the arm 31 where the seamed cans are discharged; movement being transmitted during this portion of the revolution of the can table and cage from cams 22 and 60 to release the clutches and also to lower the 100 plunger 61, thus releasing the cans to permit them to freely discharge. The rollers 51 simultaneously engage their respective cams 52 and 53, thus stopping the spindles from revolving and also securing the same 105 in a position where the chucks 14^a will be in perfect register with the cans delivered by the feeding mechanisms 30.

The seamer is capable of continuous operation and a double output inasmuch as it 110 simultaneously receives two cans, discharges two cans and also permits both the first and second operation rollers to operate in unison on their respective sets of cans. A comparatively large number of cans may in this manner be handled per minute, while the revolution and seaming speed of the rollers 32 and 33 may be comparatively slow; the machine being subjected to comparatively little vibration under these conditions as the intermittent speed transmitted through the "Geneva" movement may only be half of an ordinary seamer if the number of cans desired does not have to exceed that of an ordinary machine and a slight increase in 115 speed will, of course, immediately begin to increase the output, double the output being obtained the moment the speed of the "Geneva" movement reaches that of an ordinary seamer. 120 125 130

The gear transmission here shown is practically all located below the base plate of the machine, thus bringing the weight down and steadyng the machine and as all the 5 gears may be perfectly enclosed and housed within the base plate, it can readily be seen that it may be packed with grease or other lubricant to permit a perfect lubrication of the revolving parts. By using a worm drive 10 such as shown it becomes possible to employ a high speed driving shaft. The driving pulleys may, therefore, be lighter and the belting narrower, in this way reducing the main shaft pulleys and overhead gear to a 15 considerable extent.

The construction shown also permits the machine to be readily adjusted for different sized cans, the only operation required being that of changing the spindle chucks 14^a 20 to raise the spindle cage which is accomplished by removing a key 70 and turning the cage which will either rise or fall, due to the threads 71 formed on the lower sleeve-like extension of the cage, the cage being secured in its adjusted position by again inserting the key 70. If the height of the can is increased, it is only necessary to adjust the screws 43 to raise the seaming rollers into alignment with the can ends to be 25 30 seamed and if the diameter is increased or decreased it is only necessary to adjust the screws 44 which move the cylinders 34 to or away from the spindles. The final adjustment, as far as the seaming rollers are concerned, is taken care of by the screws 47.

The spindles employed are held firmly in place by a ball bearing 72.

One of the important features of the present invention is the application of pneumatic pressure for the purpose of holding the seaming rollers in operating position. This is very important particularly when handling square or oval cans as it permits the rollers and the pistons to yield or freely 40 45 50 reciprocate within the cylinders when the cans are being revolved by the spindles during the seaming operation. The pressure on the rollers remains, practically speaking, constant as the pipes 41 supplying the flexible tubes 38 with air are connected with comparatively large reservoirs or tanks either formed on the base as described or located at any convenient point; that is, a slight rearward movement of the piston will, 55 60 65 of course, compress the air to a certain extent, but as the volume is large the pressure is not noticeably affected and it may, therefore, be stated that a constant pressure is maintained on each seaming roller and that the pressure on one set of rollers may be different from another set as the different rollers are connected to separate sources of supply. This is also important, as previously described, as it is often necessary to exert more pressure on one roller than on

another and as the pressure in either instance may be adjusted to a nicety it has been proven that the most perfect seaming operation is permitted.

There are only four seaming rollers employed in the present instance and as these rollers operate on eight spindles sixteen finished cans per revolution of the table are obtained. Where endwise pressure is exerted it is taken care of by ball thrust bearings. For instance, the vertical driving shaft 17 is supported by a ball or button bearing 80, the spindle cage and can table are supported upon a ball race 81, each plunger or can plate 61 is supported by a ball or button bearing 82, and each spindle is secured against endwise movement by the ball thrusts 72, similar thrust bearings being interposed between each clutch member 21 and the collars 21^a.

The friction produced by end thrust and also by revolving the different parts of the machine is in this manner reduced to a minimum, thereby decreasing the actual driving power required to a minimum and at the same time providing a construction which will practically last indefinitely as any wear produced may be readily taken up wherever required.

The provisions of the flexible tubes 38 in the cylinders 34 is not an absolute necessity as it is possible to provide the pistons with rings and to apply the air pressure directly within the cylinders. The flexible tubes 38, however, are preferable as they form a flexible air connection between the pistons and the source of supply which may be perfectly airtight, thus eliminating the necessity of employing a continuously operating air compressor and automatic relief valves for maintaining predetermined pressures after these have once been ascertained.

While a specific driving mechanism is here shown, as far as the can table, spindle cage and the spindle proper are concerned, I wish it understood that any other suitable form of drive may be employed and also that the materials and finish of the several parts of the machine may be such as the experience and judgment of the manufacturer may dictate.

While no specific mechanism has been described for the purpose of removing the cans when seamed from the spindle chucks, I wish it understood that any suitable means may be provided. For instance, a plunger 90 may be centrally positioned within each spindle and reciprocally mounted therein, each plunger being normally held in a raised position by a spring 91 and depressed when moving into engagement with a stationary cam 92. This cam may be supported directly by the stationary bed plate or by any other suitable means, and in the present instance the machine should have two cams 130

so that two cans may be simultaneously released and discharged.

Having thus described my invention, what I claim and desire to secure by Letters 5 Patent is—

1. In a seaming machine the combination with a spindle adapted to receive and revolve a can, of a floating seaming member adapted to engage the flange on the can to 10 seam the same and adapted to move radially with relation thereto, said radial movement of the seaming member being imparted thereto by the periphery of the can, means for maintaining a predetermined spacing between the seaming member and the can, and means for maintaining a predetermined and constant pressure on the seaming member regardless of the positions assumed during its radial movement.
2. In a seaming machine the combination with a spindle adapted to receive and revolve a can, of a floating seaming member adapted to engage the flange on the can to seam the same. Said seaming member having a radial 25 movement imparted thereto by the periphery of the can, means for maintaining a predetermined spacing between the seaming member and the can, and pneumatically actuated means for maintaining a continuous and constant pressure on the seaming member regardless of the position assumed by the seaming member during its radial movement.
3. In a seaming machine, the combination with a revolving spindle cage and a spindle journaled therein adapted to receive and revolve a can, of a pair of cooperating seaming members mounted in the path of travel of the spindle, means for maintaining 35 a constant and continuous pneumatic pressure on one seaming member, and independent means for maintaining a constant continuous pneumatic pressure on the other seaming member.
4. In a seaming machine, the combination with a revolving spindle cage and a spindle journaled therein adapted to receive and revolve a can, of a pair of cooperating seaming members mounted in the path of travel 40 of the spindle, and a yielding pneumatic mounting for each seaming member to permit each seaming member to be independently actuated by the periphery of the can, said yielding mounting also adapted to maintain a constant pressure on the seaming member.
5. In a seaming machine, the combination with a revolving spindle cage and a spindle journaled therein adapted to receive and revolve a can, of a pair of cooperating seaming members mounted in the path of travel 45 of the spindle, a yielding mounting for each seaming member to permit each seaming member to be independently actuated by the periphery of the can, and pneumatic means

for maintaining a constant pressure on each seaming member, said pressure being greater on one than on the other.

6. In a seaming machine, the combination with a revolving spindle cage and a spindle journaled therein adapted to receive and revolve a can, of a pair of cooperating seaming members mounted in the path of travel of the spindle, a yielding mounting for each seaming member to permit each seaming 70 member to be independently actuated by the periphery of the can, pneumatic means for maintaining a constant pressure on each seaming member, said pressure being greater on one than on the other, and independent means for regulating the pressure on each seaming member.

7. A seaming machine comprising a main frame, a can receiving table, a spindle cage, a plurality of spindles journaled in the cage, means for intermittently rotating the can receiving table and spindle cage in unison, a plurality of seaming members movable on a horizontal plane with which the spindles are adapted to register, means for revolving 85 the spindles when in register with the seaming members and pneumatic actuated means for maintaining a constant pressure on the seaming members.

8. A seaming machine comprising a main frame, a can receiving table, a spindle cage, a plurality of spindles journaled in the cage, means for intermittently rotating the can receiving table and spindle cage in unison, a plurality of stationary seaming members 100 with which the spindles are adapted to register, a yielding pneumatic mounting for the seaming members, and means for revolving the spindles when in register with the seaming members.

9. A seaming machine comprising a main frame, a can receiving table, a spindle cage, a plurality of spindles journaled in the cage, means for intermittently rotating the can receiving table and spindle cage in unison, a plurality of stationary seaming members with which the spindles are adapted to register, a yielding mounting for each seaming member to permit each seaming member to be movably actuated by the periphery of the 110 can to be seamed, means for maintaining a constant pneumatic pressure on each seaming member, and means for revolving the spindles when in register with the seaming members.

10. A seaming machine comprising a main frame, a can receiving table, a spindle cage, a plurality of spindles journaled in the cage, means for intermittently rotating the can receiving table and spindle cage in unison, a plurality of stationary seaming members with which the spindles are adapted to register, a yielding mounting for each seaming member to permit each seaming member to be independently actuated by the periph- 115 120 125 130

ery of the can to be seamed, means for exerting a constant air pressure on each yielding mounting, and means for revolving the spindles when in register with the seaming members.

11. A seaming machine comprising a main frame, a can receiving table, a spindle cage, a plurality of spindles journaled in the cage, means for intermittently rotating the can receiving table and spindle cage in unison, a plurality of stationary seaming members with which the spindles are adapted to register, a plurality of cylinders, a reciprocally mounted piston in each cylinder, 10 a connecting rod pivotally mounted in each piston forming a carrier for each seaming member, means for exerting a constant pressure on each piston to permit each piston carrying a seaming member to be movably 15 actuated by the periphery of the can to be seamed, and means for revolving each spindle when in register with each seaming member.

12. A seaming machine comprising a main frame, a can receiving table, a spindle cage, a plurality of spindles, journaled in the cage, means for intermittently rotating the can receiving table and spindle cage in unison, a plurality of stationary seaming members 20 with which the spindles are adapted to register, a plurality of cylinders, a reciprocally mounted piston in each cylinder, a connecting rod pivotally mounted in each piston forming a carrier for each seaming member, 25 and means for exerting a constant fluid pressure on each piston member to permit each piston and seaming member carried thereby to be movably actuated by the periphery of the can to be seamed.

13. A seaming machine comprising a main frame, a stationary column mounted in the frame, a can receiving table journaled to rotate about said column, a spindle cage also journaled to rotate about the column, means 30 for intermittently rotating the can receiving table and the spindle cage in unison, a plurality of spindles journaled in the spindle cage, a plurality of seaming members movable on a horizontal plane carried by the main frame with which the spindles are adapted to register during the intermittent movement of the spindle cage and can receiving table, means for transmitting a revolving movement to the spindles when in 35 register with the seaming members, and pneumatic actuated means for maintaining a constant pressure on the seaming members and permitting advance and receding movement of the seaming members when engaging square or oval shaped cans.

14. A seaming machine comprising a main frame, a stationary column mounted in the frame, a can receiving table journaled to rotate about said column, a spindle cage also 40 journaled to rotate about the column, means

for intermittently rotating the can receiving table and the spindle cage in unison, a plurality of spindles journaled in the spindle cage, a plurality of stationary seaming members carried by the main frame with which the spindles are adapted to register during the intermittent movement of the spindle cage and can receiving table, means for transmitting a revolving movement to the spindles when in register with the seaming members, and means for positively locking the spindles against revolving movement when out of register with the seaming members.

15. A seaming machine comprising a main frame, a stationary column mounted in the frame, a can receiving table journaled to rotate about said column, a spindle cage also journaled to rotate about the column, means for intermittently rotating the can receiving table and the spindle cage in unison, a plurality of spindles journaled in the spindle cage, a plurality of stationary seaming members carried by the main frame with which the spindles are adapted to register during the intermittent movement of the spindle cage and can receiving table, a continuously revolving drive shaft journaled interiorly of the stationary column, means for transmitting a continuous revolving movement from said shaft to a driving member turnably mounted on each spindle, a clutch on each spindle, and means for automatically throwing said clutches into and out of engagement with the driving members on the spindles to intermittently rotate each spindle.

16. A seaming machine comprising a main frame, a stationary column mounted in the frame, a can receiving table journaled to rotate about said column, a spindle cage also journaled to rotate about the column, means for intermittently rotating the can receiving table and the spindle cage in unison, a plurality of spindles journaled in the spindle cage, a plurality of stationary seaming members carried by the main frame with which the spindles are adapted to register during the intermittent movement of the spindle cage and can receiving table, a continuously revolving drive shaft journaled interiorly of the stationary column, a gear secured on said shaft, a gear turnably mounted on each spindle intermeshing with said gear and adapted to be continuously revolved by said gear, a clutch member on each spindle gear, a second clutch member slidably mounted on a feather on each spindle, and means for automatically throwing said clutches into and out of engagement to intermittently rotate the spindles.

17. A seaming machine comprising a main frame, a stationary column mounted in the frame, a can receiving table journaled to rotate about said column, a spindle cage also

5 journaled to rotate about the column, means for intermittently rotating the can receiving table and the spindle cage in unison, a plurality of spindles journaled in the spindle cage, a plurality of stationary seaming members carried by the main frame with which the spindles are adapted to register during the intermittent movement of the spindle cage and can receiving table, a continuously 10 revolving drive shaft journaled interiorly of the stationary column, a gear secured on said shaft, a gear turnably mounted on each spindle intermeshing with said gear and adapted to be continuously revolved by said 15 gear, a clutch member on each spindle gear, a second clutch member slidably mounted on a feather on each spindle, a rocker arm pivotally mounted adjacent to each spindle, one end of each rocker arm being pivotally 20 connected with the last named clutch members and the opposite end of each arm having a roller, and a stationary cam member carried by the column with which each roller engages to automatically move the spindle 25 clutches into and out of engagement with each other.

18. A seaming machine comprising a main frame, a stationary column mounted in the frame, a can receiving table journaled to rotate about said column, a spindle cage also journaled to rotate about the column, means for intermittently rotating the can receiving table and the spindle cage in unison, a plurality of spindles journaled in the spindle 30 cage, a plurality of stationary seaming members carried by the main frame with which the spindles are adapted to register during the intermittent movement of the spindle cage and can receiving table, means for 35 transmitting a revolving movement to the spindles when in register with the seaming members, and means for positively locking the spindles against revolving movement when 40 out of register with the seaming members, said means also adapted to positively stop each spindle so that it will assume a predetermined position with relation to a can to be seamed when this is delivered to the machine.

45 19. A seaming machine comprising a main frame, a stationary column mounted in the frame, a can receiving table journaled to rotate about said column, a spindle cage also journaled to rotate about the column, means for intermittently rotating the can receiving 50 table and the spindle cage in unison, a plurality of spindles journaled in the spindle cage, a plurality of stationary seaming members carried by the main frame with which 55 the spindles are adapted to register during the intermittent movement of the spindle cage and can receiving table, means for transmitting a revolving movement to the spindles when in register with the seaming 60 members, means for positively locking the 65

spindles against revolving movement when out of register with the seaming members, said means also adapted to positively stop each spindle so that it will assume a predetermined position with relation to a can to be seamed when this is delivered to the machine, means for securing each spindle against endwise movement, a spindle chuck secured on the lower end of each spindle, means for delivering cans to be seamed to the can receiving table, and means for raising each can into engagement with a spindle chuck.

20. A seaming machine comprising a main frame, a stationary column mounted in the frame, a can receiving table journaled to rotate about said column, a spindle cage also journaled to rotate about the column, means for intermittently rotating the can receiving table and the spindle cage in unison, a plurality of spindles journaled in the spindle cage, a plurality of stationary seaming members carried by the main frame with which the spindles are adapted to register during the intermittent movement of the spindle cage and can receiving table, means for transmitting a revolving movement to the spindles when in register with the seaming members, means for positively locking the spindles against revolving movement when out of register with the seaming members, said means also adapted to positively stop each spindle so that it will assume a predetermined position with relation to a can to be seamed when this is delivered to the machine, means for securing each spindle against endwise movement, a spindle chuck secured on the lower end of each spindle, means for delivering cans to be seamed to the can receiving table, means for raising each can into engagement with a spindle chuck, said means comprising a stationary cam track formed on the main frame, a plurality of plungers carried by the can receiving table, and a roller carried by each plunger engageable with the stationary cam track to raise and lower the plungers.

21. The combination with a spindle cage in a seaming machine, of a plurality of spindles journaled in the spindle cage, a driving member turnably mounted on each spindle, means for continuously rotating said driving members, a clutch member slidably mounted on a feather on each spindle, a spindle chuck on each spindle, means for automatically throwing each clutch into engagement with the driving member to rotate each spindle, and means for positively locking each spindle against rotation, said means also adapted to stop the spindle so that the spindle chucks will assume a predetermined position when the spindles are remaining at rest.

22. The combination with a spindle cage in a seaming machine, of a plurality of

- spindles journaled in the spindle cage, a driving member turnably mounted on each spindle, means for continuously rotating said driving members, a clutch member 5 slidably mounted on a feather on each spindle, a spindle chuck on each spindle, a cam member adapted to automatically move each clutch member into and out of engagement with each driving member to intermittently 10 rotate each spindle, a second cam member, and a radially projecting arm on each clutch member adapted to engage said last named cam to positively lock each spindle against rotation.
- 15 23. The combination with a spindle cage and the spindles journaled therein, of means for delivering a can to each spindle, a seaming member support comprising a cylinder, a piston reciprocally mounted in the 20 cylinder, a connecting rod pivotally mounted in the piston, a seaming roller journaled to rotate on the connecting rod, a flexible tubing secured to the inner end of the piston, and means for maintaining a constant fluid 25 pressure within the flexible tubing.
24. In a seaming machine, a stationary frame, a can receiving table journaled to rotate in the frame, a spindle cage also journaled to rotate in the frame, a plurality of 30 spindles journaled in the spindle cage, means for intermittently rotating the can receiving table and the spindle cage in unison, a pair of stationary first operation seaming rollers carried by the stationary frame and positioned diametrically opposite to each other, a pair of stationary second operation seaming rollers carried by the stationary frame and also positioned diametrically opposite to each other, means for delivering a pair 35 of cans to the can receiving table at points diametrically opposite to each other, means for revolving the spindles when assuming positions in alignment with the seaming rollers, means for maintaining the spindles 40 at rest when out of alignment with the seaming rollers, and means for discharging cans at diametrically opposite points.
25. In a seaming machine, a can receiving table, a spindle cage mounted above the 45 table, a plurality of spindles journaled in the spindle cage, a spindle chuck on each spindle, means for delivering a pair of cans in unison to the can receiving table, means for raising the cans into engagement with the spindle chucks in unison, means for transmitting a step by step movement to the spindle cage and can receiving table so that the cans when received may be moved into alignment with a pair of stationary first 55 operation seaming members, means for rotating the spindles in alignment with the first operation seaming members, a pair of second operation seaming members with which the spindles are also adapted to align, 60 means for continuously revolving the spindles while in alignment with the first and second operation seaming members, means for positively locking the spindles against rotation during the remaining movement of the can receiving table and spindle cage, and means for discharging a pair of cans in unison. 70
26. A seaming member comprising a piston, a cylinder in which said piston is reciprocally mounted and guided, a connecting rod pivotally carried by the piston, a seaming roller journaled in the outer end of said connecting rod, a bell crank pivotally attached to the cylinder, a pivotal connection between one end of the bell crank and the connecting rod, an adjusting screw carried by the opposite end of the bell crank adapted to limit the outward movement of the piston, and means for exerting a constant pressure on the piston. 75
27. A seaming member comprising a piston, a cylinder in which said piston is reciprocally mounted and guided, a connecting rod pivotally carried by the piston, a seaming roller journaled in the outer end of said connecting rod, a bell crank pivotally attached to the cylinder, a pivotal connection between one end of the bell crank and the connecting rod, an adjusting screw carried by the opposite end of the bell crank adapted to limit the outward movement of the piston, and means for exerting a constant fluid pressure on the piston. 80
28. A seaming member comprising a piston, a cylinder in which said piston is reciprocally mounted and guided, a connecting rod pivotally carried by the piston, a seaming roller journaled in the outer end of said connecting rod, a bell crank pivotally attached to the cylinder, a pivotal connection between one end of the bell crank and the connecting rod, an adjusting screw carried by the opposite end of the bell crank adapted to limit the outward movement of the piston, a flexible tube secured at one end to the piston, a stationary head to which the opposite end of the tube is secured, and a pipe connected at one end with said head and at the opposite end with a tank which is adapted to contain a fluid under pressure. 85
29. In a seaming machine, a revolving spindle cage, a spindle journaled therein and adapted to receive and revolve a can, a cylinder mounted adjacent the path of travel of the spindle, a piston in the cylinder, means for exerting a constant fluid pressure thereon and a seaming roller supported by the piston engageable with the can. 90
30. In a seaming machine, a revolving spindle cage, a spindle journaled therein and adapted to receive and revolve a can, a cylinder mounted adjacent the path of travel of the spindle, a piston in the cylinder, means for exerting a constant fluid pressure 95

thereon and a seaming roller supported by the piston engageable with the can, and adjustable means for limiting the outward movement of the piston in the cylinder.

5 31. In a seaming machine, a revolving spindle cage, a spindle journaled therein and adapted to receive and revolve a can, a cylinder mounted adjacent the path of travel of the spindle, a piston in the cylinder,

10 means for exerting a constant fluid pressure thereon and a seaming roller supported by the piston engageable with the can, and means for adjusting the position of the cylinder radially with relation to the spindle

15 cage.

32. In a seaming machine, a revolving spindle cage, a spindle journaled therein and adapted to receive and revolve a can, a cylinder mounted adjacent the path of

20 travel of the spindle, a piston in the cylinder, means for exerting a constant fluid pressure thereon and a seaming roller supported by the piston engageable with the can, means for adjusting the position of the

25 cylinder radially with relation to the spindle cage, and means for adjusting the vertical position of the cylinder with relation to the spindle cage.

33. In a seaming machine, a revolving spindle cage, a spindle journaled therein and adapted to receive and revolve a can, a cylinder mounted adjacent the path of travel of the spindle, a piston in the cylinder, means for exerting a constant fluid

pressure thereon and a seaming roller supported by the piston engageable with the can, means for adjusting the position of the cylinder radially with relation to the spindle cage, means for adjusting the vertical position of the cylinder with relation to the spindle cage, and adjustable means for limiting the outward movement of the piston in the cylinder.

34. A seaming machine comprising a main frame, a can receiving table, a spindle cage, a plurality of spindles journaled in the cage, means for intermittently rotating the can receiving table and spindle cage in unison, a plurality of seaming members with which the spindles are adapted to register, a plurality of cylinders, a reciprocally mounted piston in each cylinder, a connecting rod in each piston forming a support for each seaming member, means for exerting a constant fluid pressure on each piston to permit each piston carrying a seaming member to be guided by the periphery of the can to be seamed, and means for revolving each spindle when in register with each seaming member.

In testimony whereof I have hereunto set my hand in the presence of two subscribing witnesses.

SAMUEL McCULLOCH.
